UNITED STATES PATENT OFFICE

2,126,720

SCAFFOLD

David E. Beatty and Ingar G. Rambo, Wauwatosa, Wis., assignors, by mesne assignments, to Safeway Steel Scaffolds Co. of America, Wilmington, Del., a corporation of Delaware

Application February 1, 1937, Serial No. 123,394

6 Claims. (Cl. 304—2)

This invention relates to scaffolds and more particularly to a tubular scaffold and to a means to adjust the scaffold for irregularities in foundation or working level.

5 In erecting scaffolds made of standard size end frames, such as the one shown and described in the patent to Reinhold A. Uecker, Patent No. 2,043,498, patented June 9, 1936, considerable difficulty has been experienced in making adjustments for variations in the foundation level, and in making adjustments in the level of the working platform.

10 End frames approximately five feet high have been found to be very satisfactory, since that size end frame is rigid, light enough in weight to permit ready handling, and large enough to insure rapid erection.

15 In the past, two methods have been used to adjust tubular scaffolds to definite heights. One method employs telescoping tubing with a pin passing through both tubes. In this construction, illustrated in the United States patent to Mosher, Patent No. 1,552,333, the pin is apt to shear or to work loose, and in either event the scaffold 20 would fall and endanger the workmen.

25 The other method, also illustrated in the Mosher patent, employs a screw and nut to adjust the height of the legs. This construction is unsafe due to the likelihood of children loosening the screws while playing on the scaffold after 30 working hours and causing the scaffold to collapse.

35 One object of the present invention is, therefore, to provide a means to adjust the platform height of a scaffold which will be secure against collapsing.

40 Another object is to provide an adjustable footing for a scaffold which will be secure against collapsing.

45 A further object is to provide a means to adjust the platform height which will be simple to erect, and inexpensive to manufacture.

50 A further object is to produce a sectional scaffold comprising a plurality of end frames superimposed on each other with an adjustment to permit an uninterrupted platform to be built at any height.

55 A further object is to produce a sectional scaffold composed of a plurality of end frames superimposed on each other and adapted to retain a sloping platform on top of the scaffold.

Further objects will be apparent upon considering the following specification, which, taken in 55 connection with the accompanying drawings, are

illustrative of a preferred form of the invention.

In the drawings:

Fig. 1 is an elevational view of a scaffold embodying the invention.

Fig. 2 is a cross-section on the lines 2—2 and 3—3' of Fig. 1, looking in the direction of the arrows.

Fig. 3 is an enlarged cross-section showing the means to adjust the upper end of the scaffold.

Fig. 4 is a view similar to Fig. 3 showing the 10 foot adjustment.

Fig. 5 shows an alternate form of footing adjustment.

Referring to Figs. 1 and 2 it will be seen that the scaffold is composed of a plurality of end frames 10 each of which comprises two vertical tubular posts 11—11, spaced from each other and joined by two horizontal braces 12—12, and stiffened by diagonal braces 13—13.

The end frames 10 may be superimposed on 20 each other, and joined by coupling pins 14, best shown in Figs. 3, 4 or 5.

Cross braces 15 join the sections as shown in Fig. 1 to support the end frames in vertical position. The cross braces are secured to the end 25 frames 10 by bolts 16 which are welded to the end frames and thus form an integral part thereof.

All of the above structure is part of and is fully 30 described in the Uecker patent, supra.

It is obvious that, where the end frames are a uniform size means must be provided to make 35 adjustments to the bottom end frames in order to compensate for differences in elevation of the foundation. Two methods of accomplishing this adjustment are shown in Figs. 4 and 5.

Referring to Fig. 4, the scaffold is provided with a base plate 20' to which is attached a coupling tube 21 of suitable diameter to fit snugly within the tubular post 11. A spacer sleeve 22 40 made of the same size tubing as the posts 11 fits over the tube 21 and spaces the bottom of the post 11 from the base plate 20'.

In practice, it has been found impractical to 45 have the sleeve over three feet long as the unsupported leg tends to wobble slightly and make the scaffold insecure. For lengths of three feet or over, a supplemental half frame 25 may be provided, as shown in Figs. 1 and 2, and the tubular 50 extensions added to the lower end of the half frame. Small irregularities from one to four inches may be taken care of most readily by blocking up the footing with planks.

The half frames 25 are connected by cross 55

braces 26 similar to the braces 15 used with the end frames 10.

A second method of adjusting the footing is shown in Fig. 5. As shown in that figure, a coupling pin 14 joins the end of the post 11 to a spacer sleeve 30 of suitable length, and a regular stationary footing member 20 is fitted into the lower end of the sleeve.

The footing member 20 comprises a base plate 10 on which is fixed a tubular shank 24. The shank may contain a spring retaining member (not shown) to prevent disengagement of the base plate from the scaffold if desired. This base plate is shown and described more fully in the co-pending application of Ingar G. Rambo and Fred H. Graser, Serial No. 90,712, filed July 15, 1936.

A half frame 25 may also be inserted between the spacer sleeve 30 and the frame 10 if necessary.

20 The top of the scaffold may be adjusted in height as shown most clearly in Figs. 2 and 3. If the adjustment is to be three feet or more the half frame 25 is used, which is similar to the half frames used at the base of the scaffold. The 25 half frame is made approximately one half the height of a regular end frame 10 and may have either one or more horizontal braces 33 to lend rigidity or to support planking such as 35 (Fig. 1).

A coupling pin 40 is made of tubular material 30 of a size to fit snugly within the post 11 of the end frame 10 or the half frame 25. A collar 41 of the same size material as the post 11 is brazed on the pin 40 so as to divide it into two parts. The shorter part is approximately half the length 35 of a standard coupling pin 14 while the longer part is made sufficiently long to fit in the posts 11 with a spacer sleeve 43 of the desired length between the post 11 and the collar 41.

40 A cross brace 45 is formed with a short tubular post 47 on each end. The cross brace 45 and posts 47 form a short frame which fits over the upper end of the coupling pin 40 and forms a support for the planking 35.

45 By varying the lengths of the spacer sleeves 43 the top platform can be made to assume any desired slope or be built to any desired height.

Having thus described the invention it is obvious that it is susceptible to various changes and modifications without departing from the spirit 50 of the invention as defined in the claims. It is not, therefore, desired to limit the invention to the precise form herein shown and described, but only by the scope of the appended claims.

55 What is claimed as new and desired to secure by Letters Patent is:

1. In a scaffold having hollow posts, means to vary the height of said scaffold, said means comprising, a coupling pin slidable into and out of one of said posts, a stop member fixed on said 60 pin, and a spacing sleeve slidable over said pin

and engageable with the end of said post and said stop member to hold the post and stop in spaced relationship.

2. In a scaffold, comprising a plurality of end frames each end frame including hollow posts, 5 means to vary the elevation of the scaffold, said means comprising, an elongated coupling pin having a sliding fit within one of said posts, a stop member on said pin, and a spacer sleeve having a sliding fit over said coupling pin and engageable with both the end of the post and the stop member to hold the post and coupling member in spaced relationship.

3. In a scaffold having hollow posts, an adjustable footing member comprising, an elongated 15 pin slidably engageable with one of said posts, a base plate fixed to said pin, and a spacer sleeve slidable over the pin and directly engageable with the end of the post and the base plate to maintain the post and base plate in spaced relation- 20 ship.

4. In a scaffold having hollow posts, means to vary the height of the scaffold said means comprising, a coupling pin having a sliding fit in said hollow post, a stop member intermediate 25 the ends of said coupling pin, and a spacer sleeve having a sliding fit on said coupling pin and adapted to space the end of the hollow post from said stop member.

5. In a scaffold having a pair of hollow posts, 30 means to vary the height of the scaffold comprising, a coupling pin in each of said posts, said coupling pins having a sliding fit within the posts, a stop member intermediate the ends of each coupling pin, a spacer sleeve on each of 35 said coupling pins having a sliding fit thereon and extending between the top of the posts and the stop members to space the same from each other, and a short frame comprising a horizontal brace and connecting members, said connecting 40 members being engageable with said coupling pin, whereby said brace may support scaffold planking.

6. In a scaffold having a pair of hollow posts, 45 means to vary the height of the scaffold comprising, a coupling pin in each of said posts, said coupling pins having a sliding fit within the posts, a stop member intermediate the ends of each coupling pin, a spacer sleeve on each of said coupling pins having a sliding fit thereon and 50 extending between the top of the posts and the stop members to space the same from each other, and a short frame, said short frame comprising, a horizontal brace adapted to support scaffold planking, and a hollow member attached 55 to each end of said brace and engageable over the short end of the coupling pin to connect the brace with the remainder of the scaffold.

DAVID E. BEATTY.
